INDICATOR-WARNING LAMP

Raymond K. Stout, Dayton, Ohio

Application May 8, 1940, Serial No. 334,004

2 Claims. (Cl. 177—329)

(Granted under the act of March 3, 1883, as
amended April 30, 1928; 370 O. G. 757)

The invention described herein may be manufactured and used by or for the Government for governmental purposes, without the payment to me of any royalty thereon.

This application is similar to my Patent 2,075,068 (Illuminating means for indicating instruments) in that both provide means whereby the lamp bulb may be easily and readily removed and/or replaced without necessitating the taking apart of any elements of the instrument panel upon which it is placed.

The present invention relates to a miniature indicator or warning lamp, a reflecting surface and means for readily mounting the assembly upon a panel for indicating the position of various controls or giving a visual warning.

One of the objects of this invention is to provide a novel, easy and quickly removable means for mounting an outwardly projecting warning lamp upon a panel.

A particular object of the invention is to provide in combination a reflector and miniature lamp so positioned with respect to each other that both will glow when the lamp filament is energized.

Another object is to color this novel lamp and/or reflector in various hues in such a manner that either or both will cast off rays of light corresponding to their color.

A further object is to provide in combination an easily replaceable lamp-carrying member and reflector assembly, of which both the lamp bulb and reflector are dyed or painted the same color so as to secure a conspicuous glow which will be readily visible in the daytime and without casting objectionable glare at night.

A still further object is to provide a warning lamp readily replaceable from the front of the panel with a plain, frosted or colored jewel end cap.

The above and other objects and advantages of the invention will appear more fully herein-after from a consideration of the detailed description which follows, when taken in connection with the accompanying drawing wherein several embodiments of the invention are illustrated. It is to be expressly understood, however, that the drawing is for the purpose of illustration and description only, and is not designed or to be considered as defining the limits of the invention, reference being had to the appended claims for this purpose.

Figure 1 is a perspective view of one form of the warning lamp together with its receptacle or socket.

Figure 2 is a cross-sectional view illustrating another form of the invention, with the warning lamp located in the corner lug of an instrument.

Figure 3 is a front view of the lamp and instrument lug shown in Figure 2.

Figure 4 is still another form of the invention, illustrating an adapter which makes it possible to use commercial miniature incandescent instrument light bulbs for warning lamps.

Figure 5 is a front view illustrating the manner in which a plurality of lamps of the type shown in Figure 4 may be mounted in a single panel.

Figure 6 is another cross-sectional view, including a protective cover in the form of a lens or jewel.

Figure 7 is a front view of the lamp shown in Figure 6.

Figure 8 is a further form illustrated by a detailed cross section of the warning lamp and mounting bracket.

Figure 9 is a front view of the lamp and mounting bracket shown in Figure 8.

There is thus provided a novel removable structure adapted for use as a warning or indicating lamp whereby the said lamp is energized upon insertion or partial insertion of the structure within the receptacle, socket or instrument casing.

Referring now to the drawing, and more particularly to Figure 1, the lamp bulb 1 is mounted permanently in the protective member 2, with the reflector 3 constructed as an integral part of the assembly. The knurled portion 4 acts as a thumb hold for inserting the warning lamp assembly into its receptacle 5. An insulating bushing 6 (see also Fig. 2) extends within the member 2 and supports an end contact (not in a position to be seen in this figure but similar to the contact 20 shown in Fig. 2). One end of the bulb filament is connected to this contact while the other end is connected to the member 2 which serves as the other contact. The thread 7 is for securing the warning lamp to the receptacle 5 which in turn is clamped to the panel by nut 8. The shield 9 houses the conductor which connects the lamp into the desired circuit.

In the instrument installation of Figures 2 and 3 the instrument is illustrated as 10, with the warning lamp mounted in the instrument lug 15. The lamp support 2 has an insulating bushing 6, which insulates contact 20 from the support. The filament 12 of the bulb 1 is connected to support 2 by means of wire 18, and to contact 20 by means of wire 19. The bulb 1 is located in the

center of reflector 3 in such a manner that the light rays will be cast to the front of the instrument and can be viewed through a large angle.

Referring now to Figures 4 and 5, the commercial instrument lamp 31 is installed in the protective mount 2 by means of insulating bushing 6. The lamp assembly is shown secured to a panel 21 and making contact with spring contact 32. The front view shown in Figure 5 illustrates how a plurality of the warning lamps may be installed upon one panel 21. The bulbs 1 are here shown with their respective reflectors 3.

Figures 6 and 7 show another modification of my invention, where the support 2 has a lamp bulb 1 and lens or jewel 38 mounted thereon. The filament 12 is connected to the support and contact 20. The insulation is shown as 6. The front view of this assembly is illustrated by the support 2 and jewel 38.

Figures 8 and 9 show a slightly different modification, with the warning lamp support 2 mounted in a bracket 43. The bulb 1 is mounted so that it extends slightly beyond the support 2. The filament 12 is connected to this mount and to contact 20. A soldering terminal 41 is attached to bracket 43, which supports soldering terminal and contact 48 through insulator 42. The insulator 6 holds the bulb in place with respect to the support and reflector 3. A front view is shown of bracket 43, protective mount support 2, reflector 3, and bulb 1.

Although several embodiments of the invention are illustrated and described, various changes which will now appear to those skilled in the art, may be made in the form and relative arrangement of the various parts without departing from the spirit and scope of the invention. Reference is therefore to be had to the appended claims for a definition of the limits of said invention.

What is claimed is:

1. A miniature warning lamp for an instrument panel or the like, comprising an externally threaded tubular protective member for mounting said lamp, said member containing a miniature lamp bulb therewithin so as to expose one end of said lamp bulb through an enlarged opening in one end of said member, said enlarged opening being provided with a reflecting surface surrounding said one end of said lamp bulb, the threads on said member being adapted to engage complementary threads in an opening in said panel or the like, a flange on said one end of said member adapted to seat against the face of said panel, the terminals of said lamp bulb being connected to contacts on said member, and said contacts being adapted to engage complementary contact means on said panel or the like when said lamp is mounted in said panel.

2. A miniature warning lamp device adapted for mounting in an instrument lug or the like, comprising a tubular metallic protective member externally threaded for mounting the device and having a bore of the approximate size of a miniature lamp bulb, a miniature lamp bulb housed within said bore and adapted to emit light from one end of said tubular member, a flanged head on said one end of said member, an opening in said head extending into said bore adjacent said lamp bulb so as to expose a portion of said bulb, a closure for said bore on the other end of said member, said closure including a contact element, an electrical connection from said lamp bulb to said metallic protective member, and an electrical connection from said lamp bulb to said contact element, all parts of said device except said flanged head being contained within the radial limits of said threaded tubular member whereby said device may be readily inserted in, or removed from, the front side of an instrument lug or the like, as a complete unit.

RAYMOND K. STOUT.
